UNITED STATES PATENT OFFICE.

SILVANUS HUSSEY, OF BRANT, NEW YORK.

WRENCH.

SPECIFICATION forming part of Letters Patent No. 475,450, dated May 24, 1892.

Application filed September 14, 1891. Serial No. 405,578. (No model.)

To all whom it may concern:

Be it known that I, SILVANUS HUSSEY, a citizen of the United States, residing at Brant, in the county of Erie and State of New York, have invented a new and useful Improvement 5 in Wrenches, of which the following is a specification.

This invention relates to an improvement in the wrench shown and described in Letters Patent of the United States No. 444,937, granted to me January 20, 1891.

The object of my present improvement is to simplify the construction of the wrench and reduce its cost of manufacture.

15 In the accompanying drawings, Figure 1 is a side elevation of the wrench. Fig. 2 is a sectional elevation thereof at right angles to Fig. 1. Fig. 3 is a longitudinal section of the head of the wrench in line $\alpha\alpha$, Fig. 2. Fig. 4 20 is a cross-section thereof in line $\gamma\gamma$, Fig. 1.

Like letters of reference refer to like parts in the several figures.

A represents the handle of the wrench, which is preferably constructed of metal and 25 slotted lengthwise to reduce its weight.

B is a stationary jaw arranged at the inner end of the handle, and C is a rectangular loop or socket formed in the inner portion of the handle in a plane parallel therewith, as shown 30 in Fig. 2.

D is a movable jaw, arranged opposite the stationary jaw B and having a rectangular shank D', which slides in the loop C of the handle. The movable jaw D is preferably 35 provided with two laterally-projecting jaws E E', each having an angular or V-shaped face, and the fixed jaw B is preferably provided with two laterally-projecting sockets or recesses F F'. In the socket or recess F is arranged a movable gripping bar or jaw f, having 40 a serrated face, which may be used in conjunction with the laterally-projecting jaw E for gripping pipes or round bars. The socket F' is preferably provided with a similarly 45 shaped jaw or bar f', having a pointed or cutting edge, which may be used in conjunction with the laterally-projecting jaw E' for cutting pipes or round bars.

G represents the rotary screw for adjusting 50 the movable jaw toward and from the fixed jaw. This adjusting-screw is attached to the

movable jaw in such manner that it is free to turn therein; but is held against moving lengthwise thereon. In the construction represented in the drawings the unthreaded upper portion of the screw is arranged in an opening formed in the movable jaw, and is held against lengthwise movement therein by a collar or shoulder g, formed on the screw and bearing against the inner side of the movable 55 jaw, and a nut g', applied to the threaded end of the screw and bearing against a shoulder formed by reducing said threaded end, as shown in Fig. 2. The threaded portion of the adjusting-screw engages in a threaded longitudinal opening h, formed partly in the fixed jaw B and partly in a boss or enlargement H, arranged at the inner portion of the handle on the front side thereof. The lower portion of the adjusting-screw is angular or flat-sided 60 and guided in a longitudinal socket or sleeve I, having a bore of corresponding shape, and which turns in an opening or bearing arranged in the cross-bar k, connecting the outer ends of the members of the slotted handle. This 65 socket projects beyond the end of the handle and is prevented from moving lengthwise in its bearing by an annular shoulder l, formed on the socket and bearing against the inner side of the cross-bar k, and a screw-nut l', applied to the screw-threaded outer end of the 70 socket and bearing against the outer face of the cross-bar k. This screw-nut also serves as a thumb-piece for turning the socket. The lower portion of the slot in the handle is enlarged to receive the socket I, as shown. Upon turning the socket I in either direction 75 by means of its thumb-piece the adjusting-screw is caused to turn in the threaded opening in the handle and move inward or outward on the latter, thereby causing the movable jaw carried by the screw to move toward or from the stationary jaw and varying the space between the jaws. The adjusting-screw is compelled to turn with the rotary 80 socket I, and is at the same time capable of sliding longitudinally in the same, thus forming a sliding connection between the adjusting-screw and the socket, which permits of a 85 compound rotary and lengthwise movement 90 of the screw.

In assembling the parts of the wrench the

socket I is first placed in its bearing and the adjusting-screw is attached to the movable jaw. The adjusting-screw is then screwed into the threaded opening of the handle and 5 its angular end fitted into the rotary socket I, and the shank of the movable jaw is at the same time guided into the loop or socket C of the handle.

By making the outer jaw movable and arranging its shank to slide in the socket formed in the upper portion of the handle the rivet-holes and rivets required for securing the shank of the stationary jaw to the handle in the patented wrench before referred to are 10 dispensed with, thus lessening the amount of labor involved in the construction and assemblage of the parts of the wrench and reducing its cost of production.

I claim as my invention—

1. The combination, with the handle and a fixed jaw arranged at the inner end thereof, of a socket formed in the handle in a plane parallel therewith, a movable jaw having a shank guided in the socket of the handle, and 15 an adjusting-screw carrying the movable jaw and arranged in a threaded opening formed in the inner portion of the handle, substantially as set forth.

2. The combination, with the handle having

a fixed jaw at its inner end and a socket or 30 loop arranged in a plane parallel with the handle, of a movable jaw having a shank guided in said socket or loop, a rotary sleeve or socket journaled in the outer portion of the handle, and a rotary adjusting-screw carrying the movable jaw, engaging in a threaded opening in the inner portion of the handle and connected with said rotary socket, substantially as set forth.

3. The combination, with the handle having 40 a fixed jaw at its inner end and a socket or loop arranged in a plane parallel with the handle, of a movable jaw having a shank guided in said socket or loop, a sleeve journaled in the outer portion of the handle and 45 having an angular bore, and a rotary adjusting-screw carrying the movable jaw, engaging in a threaded opening in the inner portion of the handle and having an angular portion which slides lengthwise in the bore of said 50 sleeve, substantially as set forth.

Witness my hand this 3d day of August, 1891.

SILVANUS HUSSEY.
